UNITED STATES PATENT OFFICE.

OHAN FRITHIOF FRANZÉN, OF TRANAS, SWEDEN.

PIN CASE.

Application filed March 27, 1925. Serial No. 18,782.

This invention has for its object a pin-case where the pins are advanced successively through an aperture in the case in order that the respective pin may be easily seized.

A form of the invention is shown in the accompanying drawing where—

Figures 1 and 2 are a vertical section of the case from two different sides,

10 Figure 3 is a plan view of the same,

Figures 4 and 5 show likewise the case in a vertical section but in different phases of the pin supplying operation.

15 1 is the case, 2 a base sleeve shaped after the case which is movable in the same, and 3 is a spring tending to move the case into its upper position shown in Figures 1 and 2 where it is supported somehow as for instance so that a nose 4 of the case is resting

20 against the upper end of a slot 5 in the sleeve 2, the nose running in the said slot during the movement of the case. The case has at its top an opening 6 for letting in the pins and a revolving cover 7 provided with

25 the supplying aperture 8 mentioned above. The bottom 9 is provided with a hole 10 for an upright 11 fixed to the bottom of the base sleeve and extending through the openings 10 and 8 when the case is pressed down to

30 the base. The said upright has a split point, see Figure 2, in order that one of the pins overlying the hole 10 may remain hanging in the upright when the case is being pressed down. In order that the pins may lodge

35 over the hole 10 the bottom is usually shaped as a groove, the said hole being provided in the bottom of same.

When a pin is to be taken out from the case the same is pressed so far downwards

40 that the upright with the pin's head extends beyond the edge of the feed opening, and then one may easily seize the pin by the same fingers by which the case is being pressed down. Figure 4 shows the position of the

45 pin immediately after it has been raised from the bottom, and Figure 5 shows the position of the pin when it is ready to be seized by the fingers. The pin is here hanging in a groove 12 of the upright, see Figure

50 2. For facilitating the automatic suspension of the pins in the upright the groove has a suitable inclination. The upright is so proportioned and shaped in such a manner that it may grasp one pin only at each

time and the pin will be resting with its head against the upper end of the upright. Further, it is so shaped as to allow the pin to be easily seized by the fingers.

When charging the case one may only observe that the pins are laid with their points downwards.

In comparison with prior cases of this kind the case described above involves the especial advantage of the pin when being fed resting against the upright with its head instead of with its point. Thereby the risk of the point being damaged is now removed. Another advantage lies in the fact that each pin after having been used may immediately be inserted again in the case, for example by the proper outlet opening.

Obviously, the case may be varied in several respects without the arrangement according to this invention being given up. So it is possible though not so practicable to let the upright be movable instead of the case and produce the movement of the upright for example by means of a small lever.

Having now described my invention, what I claim as new and desire to secure by Letters Patent is:

1. A pin case of the type wherein pins are fed out mechanically, comprising a base sleeve, a case member vertically slidable therein, an upright secured in said sleeve and projecting into said case, means on said upright for grasping a pin in said case directly under its head and advancing the same in an upright hanging position through an aperture in the top of said case, when said case is depressed in said sleeve.

2. A pin case as claimed in claim 1, wherein said upright is forked at its upper end.

3. A pin case as claimed in claim 1, wherein said means is forked at its upper end to grasp the head of a pin and provided with a vertically extending groove, adapted to receive the body of said pin when its head is grasped by said forked portion.

4. A pin case as claimed in claim 1, wherein the bottom of said case is in the form of an inclined groove.

5. A pin case of the type wherein pins are fed out mechanically, comprising a base sleeve, a case member vertically slidable therein and returnable by means of a spring in said base sleeve, a forked upright pro-

vided with a vertically extending groove, mounted in said sleeve and projecting into said case, said case having a false bottom in the form of an inclined groove adapted to support pins in an inclined position, an aperture in said bottom through which said upright projects when said case is depressed in the sleeve and an aperture in the top of

said case through which said upright ejects a pin in a vertically extending position, 10 hanging from its head in said forked portion.

In witness whereof, I have hereunto signed my name.

JOHAN FRITHIOF FRANZÉN.
